To all whom it may concern:

Be it known that I, ADOLPH PETZOLD, a citizen of the United States, residing at Philadelphia, Pennsylvania, have invented and produced a certain new and original Design for a Rug, of which the following is a full clear, and exact description, reference being had to the accompanying drawing, forming a part of this specification.

My invention relates to the surface ornamentation of woven rugs, and consists of the design therefor shown in said drawings, in which the essential and distinguishing features are a border ornamentation composed of scroll figures a, arranged to form a rectangular pattern, these scroll figures being arranged between inner and outer parallel-line borders b and c. The field center is occupied by an ornamental outline figure d, within which is a central line figure e, having opposite similar end portions f, completing the field surface.

I claim as new—

The design for a rug substantially as shown and described.

In testimony whereof I have hereunto affixed my signature this 4th day of December, A. D. 1901.
